DESIGN FOR A STAPLING MACHINE OR SIMILAR ARTICLE

Harold S. Heller, Cleveland Heights, Ohio

Application March 21, 1947, Serial No. 137,792

Term of patent 14 years

(Cl. D74—1)

To all whom it may concern:

Be it known that I, Harold S. Heller, a citizen of the United States, and a resident of Cleveland Heights, in the county of Cuyahoga and State of Ohio, have invented a new, original and ornamental Design for a Stapling Machine or Similar Article, of which the following is a specification, reference being had to the accompanying drawing, forming a part thereof.

In said drawing, Fig. 1 is a perspective view of a stapling machine or similar article showing my design; and

Fig. 2 is another perspective view of the disclosure shown in Fig. 1, the view being taken from a slightly different angle. The opposite side of the stapling machine or similar article is substantially the same as the side shown.

I claim:

The ornamental design for a stapling machine or similar article, as shown and described.

HAROLD S. HELLER.
